J. A. CRUM,
BEATING ENGINE,
APPLICATION FILED NOV. 1, 1915.

1,199,161.

Patented Sept. 26, 1916.

UNITED STATES PATENT OFFICE.

JOHN A. CRUM, OF ARLINGTON HEIGHTS, OHIO.

BEATING-ENGINE.

1,199,161.

Specification of Letters Patent. Patented Sept. 26, 1916.

Application filed November 1, 1915. Serial No. 58,944.

To all whom it may concern:

Be it known that I, JOHN A. CRUM, a citizen of the United States, and a resident of Arlington Heights, in the county of Hamilton and State of Ohio, have invented certain new and useful Improvements in Beating Engines, of which the following is a full, clear, and exact description, reference being made to the accompanying drawing, forming part of this specification.

My invention relates to beating engines for the treatment of paper pulp for use in the manufacture of paper, and the object of my invention is to provide a pulp reducing apparatus of the beating engine type which will work on the material continuously, instead of intermittently, as is the case with the ordinary beating engines.

While machines have been devised to treat paper pulp continuously, the ordinary method is to beat up the paper stock with water in what is called a beating engine, comprising an oblong tub, having a middle partition and provided with a transverse cylinder on one side of the partition rotated by power and carrying lengthwise bars for dividing and macerating the stock against a bed plate at the bottom of the tub, whence the stock is carried up over a fallblock and thence around the middle partition and back again to the beating cylinder. To prepare the average stock for the sheet machines, or the Jordan machines, takes from one and one-half to three hours, and ninety per cent. or more of that time is occupied in the stock traveling from the fallblock back to the beater, thus wasting time and power. Then in the ordinary methods, for each batch of stock, the machine has to be emptied and refilled, at the loss of time and labor. It is to overcome these objections that my invention is directed, and while I make use of the present style of beating engine, I propose to work the engine continuously and to run off by gravity the stock from the first beater into another beater of different construction where it will be fully prepared for sheet or Jordan machines in passing through the second machine.

My invention consists of that certain

novel construction and arrangement of parts to be hereinafter particularly pointed out and claimed, whereby the stock may be run continuously by gravity from the first to the second machine and be fully treated in passing through the two machines.

In the drawing, Figure 1 is a plan view of my improved machine. Fig. 2 is a transverse section taken on the lines 2, 2 of Fig. 1. Fig. 3 is a detail in longitudinal section of the inner end of the second beater.

The paper stock to be treated is deposited in the ordinary beating engine which comprises an oblong tub 1, provided with a middle partition 2, and transverse the middle of which tub is mounted the shaft 3, carrying the cylinder 4, provided with longitudinal bars 5. The beating cylinder is rotated in the usual way by a belt 6 running over pulley 7 on the outer end of the shaft 3. The paper stock to be reduced to the pulp is filled into the tub at one end and carried by the circular motion induced by the rotation of the beating cylinder underneath the cylinder where the arms crush and mash the material against the bed plate and thence the pulp mass is carried up over the backfall 8 and around in a circular path as indicated by the arrows in Fig. 1.

The beating engine thus far described is of the ordinary and well known construction. There is a cover or housing for the beating cylinder which covers the same and prevents the stock from being thrown out of the machine, but this cover has been removed from the plan view shown in Fig. 1.

My invention consists particularly in the construction and use of the second machine, which is located in close proximity to the first machine, preferably at a somewhat lower level and to which the stock from the tub 1 is supplied by gravity through the trough 9, which connects with the upper portion of the tub 1 at one end, and the supply of material delivered to the trough is controlled by the gate 10 operated by the hand wheel 11.

The second tub 13 is semi-cylindrical in shape, with an opening in the end wall for the entrance of the trough 9, and with the

discharge outlet 14 at the other end near the bottom controlled by a suitable valve. In order to clear the tub 1, the opening for the gate is carried to the bottom of the tub and the lower part of the opening is closed by a valve adapted to be opened to run off all the contents of tub 1 when a different grade of paper stock is to be prepared. The trough 9 is also extended to the bottom of tub 1, and the lower portion of the trough serves as a sand trap to catch foreign material heavier than the pulp. Mounted lengthwise and centrally through this trough is the shaft 15 carrying a series of cylindrical beater rolls 16, 17 and 18. These beater rolls are separated from each other and the beater bars are spaced somewhat closer together on the roll 17 than on 16 and closer together on 18 than on 17. The shaft 15 is journaled in a suitable framework 19, 19, at the ends, and the shaft is driven by the pulley 20 mounted thereon and belt 21 by the same power that drives the belt and pulley 6, 7, of the first tub, and the semi-cylindrical bed is covered by a semi-cylindrical housing or cover 22 properly bolted or otherwise secured on the bed 13. Baffle plates 23, 23, are secured to the inside of the cover 22 and extend down between the rolls about to the bottom of the cover, thus separating the upper half of the beater rolls and acting to retard the stock and keep it in a true rotary motion.

There are three separate bed plates 24, one for each of the three beating cylinders of the same kind that is used in the ordinary beating engine.

Of course it will be understood that suitable packing glands are employed to keep the stock from working out along the shaft 15, and that ample provision is made for the removal and replacing of the bed plates so that any one can be removed or put back independently of the others. The bed plates are preferably wider than those ordinarily used, so as to give a little more working surface.

I have made no effort in the foregoing description to either show or describe the details of the packing boxes, bolts and screws, as the manner of construction and securing of parts will be evident to any skilled mechanic.

In the use of the apparatus, the tub 1 is filled with water and paper stock in the ordinary way. After the stock has passed around the tub 1 one or more times, it will be found that the material will then be in condition to be run through the gate 11 and trough 9 into tub 13, and as the stock is run by gravity through the trough 9, the beating cylinders are rotated and the material thoroughly beaten up by the three sets of beaters, so that by the time the stock has

reached the farther end of the tub 13, it will be in condition to be discharged through the outlet. When the machine is in full operation, the level in the two tubs will be the same, and there will be a slow current continuously through the trough 9.

With this construction of apparatus, instead of taking from one and one-half to three hours to properly digest and refine the material, the pulp can be passed through the machine continuously and the stock treated in from twenty to thirty minutes.

Having thus described my invention, what I claim as new and desire to secure by Letters Patent, is:—

1. An apparatus of the character specified, comprising an oblong tub with a median partition and a cylindrical beater transverse the tub and on one side of the partition, said tub having an outlet at the upper edge, a second receptacle located slightly lower than the former, with an inlet at one end and a gravity flow from one tub to the other, a series of cylindrical beaters mounted lengthwise of said second tub, and a discharge outlet of less capacity than the inlet from the second tub at the other end.

2. An apparatus of the character specified, comprising an oblong tub with a median partition and a cylindrical beater transverse the tub and on one side of the partition, said tub having an outlet at the upper edge, a second receptacle located slightly lower than the former, with an inlet at one end and a gravity flow from one tub to the other, a series of cylindrical beaters mounted lengthwise of said second tub, with beater bars for the cylinders arranged progressively closer together for each successive cylinder, and a discharge outlet of less capacity than the inlet from the second tub at the other end.

3. An apparatus of the character specified, comprising an oblong tub with a median partition and a cylindrical beater transverse the tub and on one side of the partition, said tub having an outlet at the upper edge, with a gate to regulate the opening, a second receptacle located slightly lower than the former, with an inlet at one end and a gravity flow from one tub to the other, a series of cylindrical beaters mounted lengthwise of said second tub, and a discharge outlet of less capacity than the inlet from the second tub at the other end, with baffle plates between the beating cylinders to inclose the upper portions thereof.

4. An apparatus of the character specified, comprising an oblong tub with a median partition and a cylindrical beater transverse the tub and on one side of the partition, said tub having an outlet at the

upper edge, with a gate to regulate the opening, a second receptacle located slightly lower than the former, with an inlet at one end and a gravity flow from one tub to the other, a series of cylindrical beaters mounted lengthwise of said second tub, with beater bars for the cylinders arranged

progressively closer together for each successive cylinder, and a discharge outlet of less capacity than the inlet from the second ¹⁰ tub at the other end, with baffle plates between the beating cylinders to inclose the upper portions thereof.

JOHN A. CRUM.
